US0D1040620S

(12) **United States Design Patent** (10) Patent No.: **US D1,040,620 S**
(45) Date of Patent: ** Sep. 3, 2024

(54) **LUNCHBOX**

- (71) Applicant: **MON BENTO**, Clermont-Ferrand (FR)
(72) Inventor: **Olivier Gagneau**, Beaumont (FR)
(73) Assignee: **MON BENTO**, Clermont-Ferrand (FR)
(**) Term: **15 Years**
(21) Appl. No.: **35/517,249**
(22) Filed: **Apr. 24, 2023**

(80) **Hague Agreement Data**

Int. Filing Date: **Apr. 24, 2023**
Int. Reg. No.: **DM/228865**
Int. Reg. Date: **Apr. 24, 2023**
Int. Reg. Pub. Date: **May 19, 2023**

(30) **Foreign Application Priority Data**
